UNITED STATES PATENT OFFICE.

CHARLES W. BEMISH, OF TACOMA, WASHINGTON.

AUTOMATIC HIGH-PRESSURE ALARM.

SPECIFICATION forming part of Letters Patent No. 594,514, dated November 30, 1897.

Application filed January 9, 1897. Serial No. 618,550. (No model.)

To all whom it may concern:

Be it known that I, CHARLES W. BEMISH, a citizen of the United States, residing at Tacoma, in the county of Pierce and State of Washington, have invented certain new and useful Improvements in Safety Steam-Gage Attachments; and I do hereby declare the following to be a full, clear, and exact description of the invention, such as will enable others skilled in the art to which it appertains to make and use the same.

The object of my invention is to prevent the possibility of accident consequent upon the explosion of a boiler or the like, due to the sticking or wedging of the safety or pop valve, by apprising the attendant by an automatic alarm of the excess of pressure within the boiler over that provided for by the setting of the safety-valve.

To the accomplishment of this object my invention consists in providing a pressure-gage attached to a boiler with automatic alarm mechanism, which will be brought into operation as soon as the pressure has exceeded a predetermined limit.

In the accompanying drawings, forming a part of this specification, Figure 1 is an elevation of my safety-gage and alarm mechanism complete. Fig. 2 is a detail view of the contact-plug.

Referring to the numerals on the drawings, 1 indicates a steam-gage of ordinary construction, connected with a boiler 2 by a gage-tube 3, as shown.

4 indicates the hand or index-pointer, pivoted upon a post 5 and connected with pressure-controlled actuating mechanism well known in the art and not illustrated. The hand 4 is designed, as usual, to traverse the face of a dial 6, upon which is mounted degrees of pressure from zero to one hundred and fifty or higher.

My invention consists specifically in providing the steam-gage with what I shall term a "safety" or "alarm" dial 7, surrounding the dial 6 and provided immediately beyond each of the scale-figures upon the dial with the perforations 8, internally screw-threaded and designed for the reception of a contact-plug 9, which is illustrated in Fig. 1 and is an ordinary brass contact-plug wound near

its base with one of the wires 10 of the alarm-circuit 11. Immediately below the head of the plug 9 I provide suitable insulation 11, around which is wound a second wire 13 of 55 the alarm-circuit. It is evident that this plug may be located in the apertures 8, which correspond with the pressure at which the safety-valve is set to open, and as soon as the hand has passed the safety-point it will in 60 the event of the failure of the safety-valve come in contact with the wire 13, wound upon the insulation of the plug. The alarm-circuit will now be closed through the hand 4, its post 5, the metallic parts of the gage, including the safety-dial 7, and through the 65 plug and connected wire 10 of the alarm-circuit. Any suitable mechanism may be located within the alarm-circuit 11—as, for instance, the usual electric bell 14. 70

Ordinarily the safety-point is several degrees in advance of the bursting-point of the boiler, and it is therefore desirable that the index-pointer or hand shall remain in contact with the plug for sounding the alarm 75 continuously while the pressure is raising beyond the safety-point. To accomplish this prolonged contact between the hand and plug, I mount the former edgewise upon the dial, so as to permit it to yield, as indicated in the 80 drawings, in order to permit considerable advance movement of the post 5 without breaking the contact between the hand and the plug.

The particular form of alarm is not an essential feature of my invention, but it is obvious that any alarm mechanism which would be brought into actuation by the opening or closing of the circuit could be employed. 85

It is obvious that upon failure of the safety-valve to act at a predetermined pressure the safety-gage will cause the alarm-circuit to be closed and an alarm will be sounded in the engine-room or office or wherever desired. The plugs being detachable may be set in any 95 of the apertures 8, accordingly as the safety-valve is set at a high or low pressure.

I do not desire to limit myself to the details of construction herein shown and described, but reserve to myself the right to change, 100 modify, or vary such details within the scope of my invention.

Having thus described my invention, what I claim as new, and desire to secure by Letters Patent, is—

1. In a device of the character described, the combination with a pressure-gage provided with a non-conductive dial and with a metallic alarm-dial provided with graduated apertures, of a contact-plug, an alarm-circuit having both terminals wrapped upon the plug, one of said terminals being insulated therefrom, and a hand movable over the face of the gage and mounted edgewise, said hand being designed to make contact with the insulated terminals of the alarm-circuit and to hold said circuit closed during a predetermined movement of the hand, substantially as specified.
2. In a device of the character described, the combination with a pressure-gage provided with a non-conductive dial and with a metallic alarm-dial surrounding the same pro-

vided with graduated apertures, of a contact-plug designed to be inserted in the apertures, an alarm-circuit having its terminals wrapped upon and insulated from the plug, and a hand mounted edgewise and movable over the dial in a manner to make contact between the terminals of the alarm-circuit and to retain said circuit closed during a predetermined movement of the hand, the location of the contact-plug upon the alarm-dial and the provision of a non-conductive dial serving to prevent magnetizing of the movable parts of the gage, substantially as specified.

In testimony whereof I have signed this specification in the presence of two subscribing witnesses.

CHARLES W. BEMISII.
